UNITED STATES PATENT OFFICE.

FREDERIC R. C. BOYD, OF LYNN, MASSACHUSETTS, ASSIGNOR TO GENERAL ELECTRIC COMPANY, A CORPORATION OF NEW YORK.

SPEED-LIMITING DEVICE FOR TURBO-GENERATORS.

1,090,016.

Specification of Letters Patent. Patented Mar. 10, 1914.

Application filed September 2, 1903. Serial No. 451,313.

To all whom it may concern:

Be it known that I, FREDERIC R. C. BOYD, a citizen of the United States, residing at Lynn, county of Essex, State of Massachusetts, have invented certain new and useful Improvements in Speed-Limiting Devices for Turbo-Generators, of which the following is a specification.

This invention relates to turbo-generators, that is to say, dynamo-electric machines driven by turbine engines, both generator and turbine having a common shaft.

The idea of means involved in this invention is that of providing an artificial load which can be thrown upon the turbine when the generator load is lessened, in order to maintain the turbine load at or near a normal amount and prevent the turbine from exceeding a predetermined speed. I accomplish this by causing the turbine to drive a fan whose blades remain in a position of minimum action until a predetermined critical speed is exceeded, when they quickly move to a position of maximum action, and exert a powerful drag upon the turbine shaft, because they have changed their effective radius and curvature and increased the width of the passages between said blades.

I prefer to attach to the revolving element of the machine a plurality of blades pivotally mounted at one end near the shaft, their other ends being free to fly outwardly under the influence of centrifugal force in accordance with any acceleration in speed of said shaft above a critical point. In their inmost position the free ends of the blades lie close to fixed portions of the revolving member, such for example as the studs upon which said blades are mounted. There is then no outlet for the air between the blades, and any pressure due to the confined air is resisted by the blades, which are made preferably of resilient material, such as flexible spring-tempered steel. They are assembled with a certain amount of initial tension tending to hold them closed upon one another during low speeds. But as soon as the speed exceeds a predetermined number of revolutions per minute, the centrifugal force of these blades equals the initial tension, with the result that they start deflecting outwardly. By properly proportioning the spring-blades they will travel to the limit of their outward movement with only

a slight increase of speed on the part of the machine. This outward travel causes the blades to exert a decided retardation on the rotating element to which they are attached, so that its excess of speed is limited. Upon returning to normal speed, the spring blades again resume their closely folded position. Their action is thus one of rapid change from a minimum to a maximum of retardation and vice versa, within small changes in speed of the machine, instead of a gradual change during a considerable alteration in speed.

In the accompanying drawing, Figure 1 is a longitudinal sectional elevation of a turbine driving a generator and equipped with my speed limiting device, and Fig. 2 is a cross-section on the line 2--2, Fig. 1, on a larger scale.

The shaft 1 is common to the generator 2 and the turbine 3, one of whose bucket-wheels is shown at 4. The direction of rotation is clockwise in Fig. 2. A disk 5 is mounted on the shaft, and carries a plurality of studs 6 projecting therefrom like wrist-pins, and spaced equi-distant. To each stud is secured one end of a flat steel spring blade 7, its other end resting normally on the adjoining stud in the rear. The spring blade is given a predetermined initial tension and may be slightly curved, to keep it close to the axis of rotation at all speeds up to a predetermined maximum. Any slight increase above the critical speed causes the centrifugal force of the blade to throw it outwardly until arrested by suitable means such as a stop 8. The blade also tends to reverse its curvature, so that its tip is swung out still farther from the shaft, as shown by the dotted lines in Fig. 2. In this position the blades exert a powerful damping action on the shaft, slowing it quickly to normal speed. The additional load thrown on the turbine when the blades fly outward is due to at least three causes; first, the increased fan action, due to the higher speed; second, the increased fan action due to the greater radius of the blades, and third, the increased fan action due to the increased width of the air passages which allows a greater volume of air to be pumped and to the change in the curvature of the blades which causes a greater amount of power to be absorbed in driving them.

The fan may be utilized to cool the gener-

ator by drawing the air in through a port 9 at one end of the casing 10 inclosing said generator, and admitting it to the fan through an annular opening 11 in the end 5 of said casing concentric with the shaft. The fan may be inclosed by a wall 12 having an opening in which the disk 5 is rotatably fitted. Ribs 13 radial to the fan connect said wall with the end of the generator casing and serve to direct the air currents outwardly away from the fan. The air can escape through a hole 14 in the casing.

In accordance with the provisions of the 15 patent statutes, I have described the principle of operation of my invention together with the apparatus which I now consider to represent the best embodiment thereof; but I desire to have it understood that the 20 apparatus shown is only illustrative, and that the invention can be carried out by other means.

What I claim as new and desire to secure by Letters Patent of the United States, is,—
25 1. A speed limiting device for a prime mover comprising a fan having a plurality of tangentially arranged resilient blades, and means defining a passage for the admission of air to the blades, said blades delivering the air from between the same to the periphery thereof and being capable of swinging outward under centrifugal force when a certain predetermined speed is reached, whereby the same present an increased radius and a greater vane space.

40 2. A speed limiting device for a prime mover comprising a fan having a plurality of tangentially arranged resilient blades, means defining a passage for the admission of air to the blades, said blades delivering the air from between the same to the periphery thereof and being capable of swinging outward under centrifugal force when a certain predetermined speed is reached where-
45 by the same present an increased radius and a greater vane space, and means for causing the blades to reverse their curvature as they move outward.

3. A speed limiting device for a prime mover comprising a fan having a plurality of 50 tangentially arranged resilient blades normally curved away from the direction of rotation, means defining an annular passage for the admission of air to the blades, said blades delivering the air from between 55 the same to the periphery thereof and being capable of swinging outward under centrifugal force when a certain predetermined speed is reached, whereby the same present an increased radius and a greater vane 60 space, and means for causing the blades to reverse their curvature so they present their curved surfaces toward the direction of rotation as they move outward.

4. A speed limiting device for a prime 65 mover comprising a fan having a plurality of tangentially arranged resilient blades fixed at one end and having their free ends normally under tension tending to hold them closed upon one another, means defining a passage for the admission of air to the blades, said blades delivering the air to the periphery thereof and being capable of swinging outward under centrifugal force when a certain predetermined speed is exceeded 75 whereby the same present an increased radius and a greater vane space.

5. The combination in a speed limiting device for a prime mover, of a plurality of resilient fan blades fixed at one end and arranged around the shaft of the prime mover, said blades being under an initial tension tending to hold them close to the shaft, and means defining a passage for the admission of air to the blades, said blades being capable of swinging outward under centrifugal force when a certain predetermined speed is exceeded whereby the same present an increased radius and a greater vane space.

In witness whereof, I have hereunto set 90 my hand this 28th day of August, 1908.

FREDERIC R. C. BOYD.
